(57) **ABSTRACT**

A new *Dianthus* plant particularly distinguished by having single, red bicolor flowers, a compact growth habit, and strong branching, is disclosed.

1 Drawing Sheet

1

Genus and species: *Dianthus* sp.
Variety denomination: 'KLEDG13160'.

BACKGROUND OF THE NEW PLANT

The present invention comprises a new and distinct variety of *Dianthus*, botanically known as *Dianthus* sp. and herein-after referred to by the variety name 'KLEDG13160'. 'KLEDG13160' is a selection that results from a cross pollination of the proprietary female *dianthus* line 'DSS 2008 0052' (unpatented) and the male *dianthus* line 'KLEDG13146' (U.S. Plant Pat. No. 25,877).

In June of 2009 the proprietary female *dianthus* line 'DSS 2008 0052' and the male *dianthus* line 'KLEDG13146' were cross pollinated in Stuttgart, Germany and seeds were obtained. The seeds were sown and plants were grown for evaluation. A plant line was selected in June 2010 in Stuttgart, Germany, and named 'KLEDG13160'. In June 2010, 'KLEDG13160' was first vegetatively propagated by vegetative stem cuttings. 'KLEDG13160' was found to reproduce true to type in successive generations of asexual propagation via vegetative cuttings in Stuttgart, Germany.

SUMMARY

The following are the most outstanding and distinguishing characteristics of this new variety when grown under normal horticultural practices in Stuttgart, Germany.

1. Single, red bicolor flowers;
2. Compact growth habit; and
3. Strong branching.

2

CROSS REFERENCE TO RELATED APPLICATIONS

5 Plant Breeder's Rights for 'KLEDG13160' were applied for in Europe with the Community Plant Variety Office on Jul. 1, 2013, application number 2013/1809. 'KLEDG13160' has not been made publicly available or sold more than one year prior to the filing date of this application.

10 **DESCRIPTION OF THE PHOTOGRAPH**

15 This new *Dianthus* plant is illustrated by the accompanying photograph which shows an overall view of the plant. The colors shown are as true as can be reasonably obtained by conventional photographic procedures. The plant is about 4 to 5 months-old grown indoors in Stuttgart, Germany in April 2011.

20 **DESCRIPTION OF THE NEW VARIETY**

25 The following detailed descriptions set forth the distinctive characteristics of 'KLEDG13160'. The data which define these characteristics were collected from asexual reproductions carried out in Stuttgart, Germany. Data was collected on four month-old plants grown in a greenhouse in Stuttgart, Germany in March 2014. Color references are to The R.H.S. Colour Chart of The Royal Horticultural Society of London (R.H.S.), 5th edition (2007).

Classification:

Family.—Caryophyllaceae.

Species.—*Dianthus* sp.

Common name.—Garden carnation.

Variety.—‘KLEDG13160’.

Parentage:

Female.—The proprietary *dianthus* ‘DSS 2008 0052’.

Male.—The *dianthus* ‘KLEDG13146’ (U.S. Plant Pat. No. 25,877).

Propagation:

Type.—Vegetative stem cuttings.

Time to produce a rooted young plant.—20 days.

Root description.—White, well-branched, fine.

Rooting habit.—Lanceolate.

Plant description:

Plant form.—Potted plant, upright, bushy, compact.

Plant height.—9.0 cm.

Plant diameter or spread.—15.0 cm.

Lateral branches:

Length.—5.0 cm.

Diameter.—2.0 cm.

Internode length.—0.5 cm to 2.0 cm.

Internode number.—3 to 5.

Internode thickness.—2.0 cm to 3.0 cm.

Node length.—0.3 cm.

Node diameter.—0.3 cm.

Stem.—Solid.

Stem shape.—Round.

Texture.—Smooth.

Color.—RHS N138B.

Foliation description:

Arrangement.—Opposite.

Length.—4.0 cm.

Width.—0.4 cm.

Shape.—Lanceolate.

Apex.—Acute.

Base.—Obtuse.

Margin.—Entire.

Texture.—Upper surface: Smooth.

Venation pattern.—Parallel.

Color.—Immature and mature leaves: Upper surface:

RHS N138A. Lower surface: RHS N138B. Venation:

RHS N138D.

Flower description:

Flower type and habit.—Single, round.

Fragrance.—Present.

Natural flowering season.—Spring to Fall.

Flower longevity.—Medium, 4 to 6 days.

Position of flowers relative to foliage.—Slightly above.

Flower buds.—Length: 1.2 cm. Diameter: 0.7 cm.

Shape: Ovate. Color: Mixed, RHS 183C and RHS

137C. Extrusions of the style at bud stage: Absent.

Corolla.—Quantity of petals/arrangement: 5, radial.

Corolla height: 1.0 cm. Petal length: 3.0 cm. Petal

width: 1.8 cm. Petal shape: V-shaped. Petal apex:

Obtuse. Petal base: Cuspidate. Petal margin: Slightly

serrate; depth of margin very shallow. Petal texture:

Upper and lower surfaces: Smooth. Petal color:

Immature: Upper surface: RHS 59A to RHS 59C.

Lower surface: RHS 64A. Mature: Upper surface:

RHS 59A at the center and base with RHS 53C

towards the edge. Lower surface: RHS 64C to RHS

64D.

Calyx.—Quantity of sepals/arrangement: 5, single.

Calyx height: 1.3 cm. Calyx diameter, at the apex: 0.6

cm. Calyx shape: Cylindrical. Sepal apex shape:

Cylindrical.

5 Sepal texture.—Upper and lower surfaces: Smooth.

6 Sepal color: Upper surface: RHS 187B and RHS 137C. Lower surface: RHS 137B.

Epicalyx.—Position: Adpressed. Average length: 0.7 cm. Average width: 0.6 cm. Color: RHS 177A and RHS 136B. Apex shape: Obtuse.

Peduncles:

Length.—7.0 cm.

Diameter.—0.2 cm.

Strength.—Moderate to strong.

Texture.—Smooth.

Color.—RHS N138D.

Reproductive organs:

10 Stamens.—Quantity: Moderate to sparse. Filament length: 1.0 cm. Filament color: RHS 59A. Anther length: 0.2 cm. Anther diameter: 0.08 cm. Anther color: RHS 84D. Pollen amount: Moderate to sparse.

15 Pistils.—Quantity: 2. Pistil length: 1.6 cm. Style quantity per pistil: 2. Style shoulder: Absent. Style length: 0.1 cm. Style color: RHS 73D. Stigma shape: Filamentous. Stigma color: RHS 59A. Ovary size: 0.4 cm. Ovary shape: Ovate. Ovary color: Younger flowers are RHS 139D, mature flowers are RHS 144C. Ovary texture: Smooth. Fruits/seeds: None observed to date.

20 25 Disease and insect/pest resistance: No special observations were made.

COMPARISON WITH PARENTAL LINES AND KNOWN VARIETY

30 ‘KLEDG13160’ is a distinct variety of *dianthus*. ‘KLEDG13160’ is distinguished from its parents as described in Table 1:

35 TABLE 1

Trait	Comparison with Parental Lines		
	Variety ‘KLEDG13160’	Female parent ‘DSS 2008 0052’	Male Parent ‘KLEDG13146’
Flower type	Single	Double	Double
Growth	Compact	Medium to small	Medium
Branching	Strong	Less	Very strong

40 45 ‘KLEDG13160’ is most similar to the commercial *dianthus* plant named ‘KLEDG11143’ (U.S. Plant Pat. No. 23,150), commercially known as Everlast ‘Burgundy Blush’. Differences between the two varieties are described in Table 2:

50 TABLE 2

Trait	Comparison with Similar Variety	
	Variety ‘KLEDG13160’	Commercial line ‘KLEDG11143’
Flower type	Single	Double
Earliness	Medium	Medium to late
Branching	Strong	Medium

55 60 We claim:

1. A new and distinct variety of *Dianthus* plant named ‘KLEDG13160’ as illustrated and described herein.
